UNITED STATES PATENT OFFICE.

JAMES J. WOOD, OF BROOKLYN, NEW YORK.

ELECTRIC LAMP.

SPECIFICATION forming part of Letters Patent No. 279,512, dated June 12, 1883.

Application filed April 6, 1882. (No model.)

To all whom it may concern:

Be it known that I, JAMES J. WOOD, of Brooklyn, in the county of Kings and State of New York, have invented certain new and useful Improvements in Electric Lamps, of which the following is a specification.

This invention relates to that class of lamps in which the regulating-armature carries a vibrating train of wheels which is engaged at 5 to the leading pinion with a rack on the carbon-holder, and which has a terminal scape-wheel or detent which is brought up against a stop-tooth when the armature is attracted to separate the carbon, and is withdrawn from the 15 stop when the armature is retracted to allow the carbon to descend and the gear-train to run down to feed the carbons.

Heretofore lamps of this kind have been generally non-focusing, with one carbon only 20 engaged with and actuated by the vibrating train, the other carbon being fixed; and the object of my present invention is to provide an improved focusing-lamp of this kind, in which both positive and negative carbon-holders will be engaged with the vibrating train, 25 so that both carbons will be regulated or moved simultaneously by the motions of the train in order to keep the arc at a constant point or focus.

30 To this end the main feature of my improvement lies in a simple connection between the second or negative carbon-holder (which in this case is of course movable) and the spindle of the gear-train, which is geared with the 35 first or positive carbon-holder. This connection consists of a rotary axis or shaft mounted in stationary bearings, and geared on one side with the negative holder and on the other side with the spindle of the vibrating train which 40 meshes with the positive holder, so that as the train is vibrated up or down by the usual regulating movements both carbon-holders will be moved simultaneously in opposite directions to or from each other and at proper speeds, as 45 will be understood, thus producing a proper focusing action in a very simple manner.

The invention also embodies some minor features, as hereinafter fully set forth.

Figure 1 of the drawings annexed is a sectional elevation of my improved focusing-lamp, 50 having, however, the mechanism removed from

the "head" or mechanism-case of the lamp. Fig. 2 is an enlarged sectional elevation of the head or mechanism-case with its contained mechanism, the line of view or aspect being 55 the same as in Fig. 1, but the carbon-holders being broken off above and below the case. Fig. 3 is a sectional elevation at right angles to Fig. 2. Fig. 4 is a sectional plan of Figs. 2 and 3 with the top of the case removed. Fig. 5 is a detail showing the manner of connecting and adjusting the retracting-spring of the armature. Fig. 6 is a detail showing the insulating-coupling in the connecting-shaft between the negative holder and the vibrating train. 65

The regulating mechanism in this lamp is of precisely the same general design or type shown in several former applications filed by me and it will hence be only necessary to here briefly describe the general mechanism in order that the novel parts by which a focusing 70 action is produced with this kind of mechanism, be more fully set forth. In describing the general mechanism I would therefore first refer to Figs. 2 and 3, in which *a* indicates 75 an **H**-shaped pendent armature, which plays between two pairs of differential magnets, *i k*, of the usual tubular form, which project toward each other, respectively, from the upper and lower heads, *b b'*, of the lamp-frame, and 80 inclose the horns of the **H**-armature, as best shown in Fig. 2. This armature is pivoted at the middle by trunnion-screws to an armature-lever-frame, *d*, (see Figs. 2, 3, and 4,) which lever-frame is itself pivoted on trunnion-screws *c* between the fixed standards *e e'* of the lamp-frame, Figs. 3 and 4, and it carries the usual train of wheels *e e'*. This wheel-train *e* is itself pivoted to the armature-lever frame at its outer and lower corner on the pivot-screws *f*, as seen in Figs. 3 and 4, and the leading pinion *e'* on the first spindle, *e''*, of the train meshes with the rock-teeth on the positive carbon-holder *g*, while the terminal detent-wheel *e'''* of the train approaches a stop-tooth, *h'*, on a spring, *h*, whose inner end is fixed to a post depending from the top head, *b'*, of the lamp-frame, while its outer and free end bears upon the upper and outer corner of the wheel-train, as shown best in Fig. 3. Now, 90 the main magnet *i* is of course of low resistance and arranged in the direct or arc circuit, while 95 100

the minor magnet *k* is of high resistance and arranged in a shunt around the arc, as usual, so that when the lamp is put in circuit with the carbons together, the main magnet *i* will 5 become strongly attractive and will move the armature *a* downward and sway the armature-lever *d*, so as to bodily raise the wheel-train and bring the detent-wheel against the stop-tooth, and thus lift and sustain the 10 positive carbon-holder, and thereby produce the separation of the carbon points to form the arc. As the carbons burn away, and thus lengthen the arc, the attraction of the minor or shunt magnet *k* gradually increases, and, 15 finally, with the assistance of the retracting-spring *l*, overcomes the separating-magnet *i* and moves the armature and wheel-train in the opposite way, so as to withdraw the detent-wheel from the stop-tooth, and thus release 20 the train of wheels and allow the carbon-holder to descend and give the necessary feed to restore the arc to its normal length, and when thus restored the action of the main magnet *i* will again preponderate and bring 25 the detent-wheel against the stop-tooth, and so hold the parts until the next feed is required.

It will therefore be seen that the regulating mechanism, so far as described, may be said 30 to be precisely the same in action and construction as that used in non-focusing lamps of this class, the positive carbon-holder being raised to produce separation and allowed to descend to produce the feed in the usual way. 35 It will be noted, however, by reference to Fig. 1 in connection with Figs. 2 and 3, that instead of the positive carbon being held in the lower end of the positive holder *g*, this end of the holder terminates idly and works in a closed 40 tube, *m'*, which depends from the lower head of the lamp-frame, while the main portion of the holder is extended upwardly, in the manner usual in focusing-lamps, through a long tube, *m*, which rises from the upper head, 45 *b'*, and from the top of the holder a lateral overhanging arm, *g'*, projects, and is provided with a pendant angularly-adjustable clamp, *q*, from which the positive carbon hangs vertically, as shown fully in Fig. 1. The negative 50 carbon is held in the clamp of the negative holder *r*, which rises in line with the positive carbon out of a guide-tube, *s*, which extends from the top of the lamp-frame parallel with the guide-tube *m* of the positive holder, as 55 seen best in Fig. 1. The lower portion of the negative holder is provided with rack-teeth similar to the positive holder, as shown in Figs. 1, 2, and 3, and terminates within the mechanism-case, and may descend, when fully depressed, 60 into a short tube, *s'*, which projects from the lower head of the mechanism-case. It will be readily understood, however, that the length and stroke of the negative holder is only about half as great as that of the positive 65 holder, as may be seen from Figs. 1, 2, and 3, as is usual in focusing-lamps.

Referring now to Figs. 2, 3, and 4, it will be

seen that, according to my improvement, the rack of the negative holder meshes with a small pinion, *A*, fixed on one end of an independent spindle, *B*, which spindle is pivoted or journaled at each end in fixed bearings or hangers *C C*, which project from the head *b'*, and on the opposite end of this spindle is fixed a small gear-wheel, *D*, which gears with a pinion, *v*, on one end of the leading spindle of the gear-train, which spindle is of course geared, as before described, by a second pinion, *e'*, with the rack of the positive carbon-holder; hence this spindle *B*, with its wheel *D* and 70 pinion *A*, forms a positive operative connection which gears the negative carbon-holder with the wheel-train and regulating mechanism of the lamp, and it will be observed, on reference to Figs. 3 and 4, that this spindle is 75 geared on one side of its diameter, through the pinion *A*, with the negative holder, and on the opposite side of its diameter, through the wheel *D*, with the gear-train and positive carbon-holder, and that the gear-wheel *D* is of twice the 80 diameter of the pinions which mesh with the carbon-holders; hence whatever motions are 85 made by the leading pinions *e' v* of the wheel-train, which will of course represent the motions of the positive carbon, precisely corresponding 90 motions will be imparted to the negative carbon, but in the opposite direction and of half the extent. Thus, referring to Fig. 3, suppose 95 that the wheel-train is moved bodily upward under the impulse of the preponderating downward attraction of the main magnet *i* when 100 producing the separating movement, as indicated by arrows, the positive carbon-holder will of course be also raised bodily, and the non-rotating pinion *v* will now be moved in a 105 short tangential path, like a rack, over the gear-wheel *D*, thus partly rotating the same, and thereby slightly depressing the negative-holder *r*, so that both carbon points will thus 110 be moved or separated simultaneously and at 115 proportionate rates, and will thus produce the proper focusing action at the separating movement.

We will now consider the action of parts during the feed motion by referring to Fig. 2, 115 where the arrows represent the parts moving in the reverse direction to that indicated in Fig. 3. Thus when the wheel-train is sufficiently depressed by the preponderating attraction of the shunt-magnet so as to withdraw the detent-wheel from the stop-tooth, the gear-train will be released and the positive carbon-holder, which is of course much larger and heavier than the negative holder, will be 120 free to slowly descend under the action of 125 gravity and the retarding influence of the gear-train, and in so doing will of course revolve the leading spindle *e* of the gear-train in the direction indicated by the arrow in Fig. 2, 130 and this will of course cause the connecting-spindle *B* to revolve in the opposite direction, and thereby to raise the negative holder *r*, so that the carbon points will simultaneously approach each other, the positive descending

and the negative ascending, thus producing the proper focusing movement at the feed as well as at the separation, as will be readily understood. The arc will thus be kept at a 5 constant point or focus, notwithstanding the consumption of the carbons, and it will be readily seen that by the simple connection described between the movable negative holder and the vibrating gear-train a very efficient 10 and simple form of focusing-lamp is produced with very little more than the mechanism used in non-focusing lamps of the same type.

A sight-point, *t*, (see Fig. 1,) projects from the guide-tube *m* of the positive holder to indicate the proper focusing-point for the carbons, and thus serve as a guide when inserting fresh carbons in the holders.

As shown in Fig. 1, the standard of the lamp is provided with a means of adjustment whereby 20 the body of the lamp may be raised or lowered slightly to better adjust the focus-point of the carbons to the focus of reflectors with which the lamp may be used. This adjustment is made by turning the milled nut *w* one 25 way or the other, which nut screws upon the non-rotating stem *y*, which stem slides in the pedestal *x*, and thus raises or lowers the lamp. The nut *w* is free to turn on the top of the pedestal, but is prevented from moving up or 30 down by a stud which engages a groove around the pedestal, while the screw-stem *y* is free to rise up or down by the action of the nut *w*, but is prevented from turning by a stud which 35 engages a slot in the stem, as fully shown in Fig. 1.

The retracting-spring *l* of the armature-lever *I* prefer to adjust as shown in Figs. 4 and 5—that is, by means of an elbow-lever, *l'*, which is pivoted on the ledge of one of the standards 40 *c*, and whose short arm is first bent downward and then horizontally to overlie the side of the standard, and through this overlying end is screwed an adjusting-screw, *l''*, which bears upon the side of the standard, so that by screwing 45 this screw in or out the long arm of the lever will be moved up or down to correspondingly increase or decrease the tension of the spring, as will be understood.

The direction of the current and the arrangement of the insulation are shown best in Figs. 2 50 and 3, the insulation being indicated by granulation. The circuit-wires connect to the binding-posts + —, which depend from the lower head of the lamp, as seen in Fig. 3. The positive post is in metallic connection with the frame of the lamp, and the current hence passes through the lamp-frame and rises through the positive carbon-holder, and, passing from the positive to the negative carbon, thence descends through the negative holder and its 55 guide-tube *s*, which is insulated from the lamp-frame, as seen best in Fig. 2. The current thence passes from the lower end of the guide-tube *s* to one end of the main magnet-coils,

which is connected with said tube, as shown 65 in Fig. 2, and, flowing through the coils of said magnet, the current finally passes off by the negative post, to which the other ends of the coils connect, as seen in Figs. 2 and 3, the negative post being, of course, insulated from 70 the lamp-frame. The ends of the coils of the shunt-magnet *k* may connect, respectively, to any convenient positive and negative parts of the lamp. I prefer to connect one end with the frame of the lamp, as shown at the top of 75 Fig. 2, and to connect the opposite end with the negative binding-post, or with the end of the main magnet-coils near the binding-post, as shown in Figs. 2 and 3. The connecting-spindle *B* is electrically divided in the middle, 80 as shown in Figs. 2 and 6, by an insulating-coupling, 2 3, else it would of course form a passage for the direct flow of the current from the positive to the negative holder. This coupling, as shown in detail in Fig. 6, consists of a 85 non-conducting disk, 2, and two little metal hubs or cross-heads, 3 3, which are screwed on opposite sides of the disk at right angles to each other, so as to be out of metallic contact with each other, and in these hubs the ends of 90 the two sections of the shaft are fixed, as fully shown in Figs. 2 and 6. The end of the shaft which gears with the negative holder, as seen in Fig. 2, is stepped in a socket or bearing-screw, 4, which is insulated by the non-conducting sleeve 5 from the hanger *C*, which connects with the lamp-frame, thus preventing 95 electrical connection between the negative holder and the lamp-frame through the spindle *B*, as will be understood.

What I claim is—

1. The combination, in an electric lamp, with regulating mechanism equipped with a vibrating wheel-train meshing with one carbon-holder, of an independent rotary connection or axis 105 mounted in fixed bearings and geared with the vibrating train and with the other carbon-holder, whereby the motions imparted by the vibrating wheel-train to the first carbon-holder, or vice versa, are simultaneously imparted to 110 the second holder in the opposite direction, thereby producing a proper focusing action at the carbon points, substantially as herein shown and described.

2. The combination, with an electric lamp 115 of substantially the described kind, of the independent rotary spindle *B*, provided with a pinion, *A*, to gear with one carbon-holder, and a wheel or pinion, *D*, adapted to gear with the axis of the wheel-train which gears with the 120 other carbon holder, and divided between said wheel and pinion *B* *D* by an insulating-coupling, substantially as and for the purpose set forth.
